UNITED STATES PATENT OFFICE.

ALBERT CHARLES DAVIS, OF BOOTLE, ENGLAND.

REFRIGERATOR-DOOR.

1,389,423.

Specification of Letters Patent. Patented Aug. 30, 1921.

Application filed February 24, 1919. Serial No. 279,023.

To all whom it may concern:

Be it known that I, ALBERT CHARLES DAVIS, a subject of the King of England, residing at 20 Morningside road, Bootle, in 5 the county of Lancaster, England, have invented a certain new and useful Refrigerator-Door, of which the following is a specification.

This invention relates to doors or like 10 closures of cold storage chambers, and other rooms or chambers, or receptacles, the interiors whereof it is required to insulate from the outer air; and has for its object to provide simple means whereby a door or 15 like closure may be quickly and effectively sealed to its frame or casing—and also, in some cases to a floor—when closed.

Broadly, my invention consists in the application to a door or like closure, of two 20 or more adjustably-carried jambs or battens, the adjacent ends whereof are of such shape or configuration and so co-act with each other and with the frame or casing that, when the door is closed, and said 25 jambs or battens are projected, an effective corner seal is obtained.

Preferably mechanism is provided whereby said jambs or battens may be simultaneously projected or retracted, although, 30 if desired, they may be actuated separately and individually.

In the application of the invention to the door of a cold storage chamber or the like, I also prefer to provide means, as hereinafter described, whereby it is insured that 35 said jambs or battens shall contact with the insulated portion of the door, and the front or panel of the latter shall contact with its frame or casing.

According to one mode of embodying my 40 invention, and in its application to a cold storage chamber of the type in common use, there are provided at the top, bottom, and sides of a suitably insulated door, adjustable jambs or battens constructed of wood or other suitable material, each of which is articulated to a common—centrally disposed—metal plate, bracket, or the like.

When said door is closed, by turning said 45 central plate, bracket, or the like, through one quarter of a revolution—say, by means of a key or handle fitted on an end of a shaft or spindle extending through and operatively connected with the plate—said

jambs or battens are respectively caused to 55 be projected firmly against the top and sides of the door frame, and floor.

By a further—preferably reverse—movement of the operating handle, said jambs or battens retire from contact with the frame 60 and floor, whereupon the door may be immediately opened.

The ends of said jambs or battens are of such shape or configuration, and so co-act with each other and with the door frame 65 or casing as to obviate the leaving of through air passages at the door corners when said battens are in their operative or sealing positions.

As said jambs or battens—being self adjusting—will accommodate themselves to the framing of a door, even if such a frame be out of truth or alinement, the necessity for adjustable hinges and special fasteners, as now commonly used in connection with 75 the doors of cold storage chambers, is obviated.

Further, the employment of a fixed or loose door sill, as, heretofore usual, is obviated.

While in installations—such as cold storage chambers—it is necessary or desirable to fit four of said adjustable jambs or battens to a door or like closure, it is to be understood that in some instances I may provide two, or three, only the sealing of the 80 remaining sides or side being effected in other known suitable manner.

I will further describe my invention with the aid of the accompanying sheet of explanatory drawings which illustrate the application of my invention—by way of examples only—to the door of a cold storage chamber, and to a ship's hatch.

In said drawings:—

Figure 1 is a front elevation of the door and frame with a portion of the door broken away to show the operating mechanism.

Fig. 2 a side elevation of the door and frame with a portion of the door broken 100 away.

Fig. 3 is a sectional plan of a portion of the door and frame drawn to an enlarged scale, as compared with Figs. 1 and 2.

Fig. 4 is an elevation of a door corner 105 drawn to an enlarged scale as compared with Figs. 1 and 2, the front panel *e* being removed for the purpose of exposing adja-

cent ends of jambs or battens which, as shown, are in their fully projected or expanded positions.

Fig. 5 is a plan, and

Fig. 6 is an isometric view of the adjacent ends of the jambs or battens.

Fig. 7 is an elevation of the jamb or batten ends shown in Figs. 4 to 6 as viewed from the rear side and the door removed.

Fig. 8 being a plan of the batten ends, and

Fig. 9 an isometric perspective of a corner joint adapted to form a part of the door.

Fig. 10 illustrates, in section, a ship's hatch provided with my improvements.

Fig. 11 is a front elevation,

Fig. 12 is a plan, and

Fig. 13 is a side elevation of an insulated railway van provided with a door according to my invention.

In the several views like characters of reference denote like or equivalent parts wherever they occur.

Referring first to the door and frame construction illustrated in Figs. 1 to 5, *a* denotes the top, and *b*, *b* the sides of the door framing of a cold storage chamber; *c* indicates the floor. The door, which is secured to the frame by hinges *d*, *d* comprises a front panel *e* and an insulated portion *f*, between which are arranged the upper horizontal jamb or batten *g*, the lower horizontal batten *h* and the side vertical battens *i*, *i*. Said battens are articulated to a common plate *j* by means of the forks *k*, *k*¹, rods *m*, *m*¹, and connecting pins *l*; a fork *k* being secured to a plate *j* and a rod *m* and a fork *k*¹ being secured to a rod *m* and a batten carrying rod *m*¹. Operatively connected with said plate *j* is a spindle *n*. *c* (Fig. 1) indicates an angle plate which constitutes a stop for the upper vertical rod *m*, and thus limits the rotary motion of plate *j*. At each inner corner of the door frame there is fitted a triangular piece *q* of wood or other suitable material.

On referring more particularly to Figs. 4 to 9 inclusive, it will be seen that an end of one of the jambs or battens (*g* in the case illustrated) has been cut longitudinally through the middle to form a lap piece *g*¹; a wedge like projection *g*² is also created, and the corner of said lap piece is removed, as indicated at *g*³; the angle at which the face of said wedge like projection *g*² and corner *g*³ of lap piece *g*¹ is cut is 45°.

The adjacent end of another jamb or batten (*i* in the case illustrated) is cut longitudinally through the middle to form a lap piece *i*¹, and alternate corners at *i*², *i*³, are removed at an angle of 45°. Said wedge piece *g*² is adapted to "take" in the space *i*⁴ when said jambs or battens are in their retracted or collapsed positions. When pro-

jected batten *g* "expands" upwardly and batten *i* laterally from the door, the two faces *g*³, *i*³, meeting and bearing against the corner piece of the frame, said corner piece being of length sufficient to receive both faces, thus as said battens are designed to project only partially beyond the door, an effective corner seal is obtained.

In Fig. 4 a line of light is shown for the purpose of illustration, between the batten corner faces *g*³, *i*³, and the frame corner piece *q* but it will be understood that in use these faces will be in close contact.

As illustrated in the drawings, the battens are in their projected positions (having been moved thereto by means of a handle or key fitted on one or other of the squared extremities of the plate-spindle *n*) extending in part beyond the insulated portion of the door and bearing respectively against the top *a*, sides *b*, and corner pieces *q* of the frame, and the floor *c*; thus the door is sealed. By a reverse movement of the handle the battens are retracted, the door being thereby unsealed and released.

In the drawings the jambs or battens are shown fully expanded; in actual practice, however, it will rarely occur that they will reach their maximum limit of outward movement.

p, *p*, denotes wedge pieces constructed of spring steel which are secured in the framing and project outwardly; corresponding passages *p*¹ are secured in the battens into which said wedges "take" or engage, when the battens are projected; by this means it is insured that the battens contact with the insulated portion of the door and at the same time the front or panel of the door is brought into contact with the door frame.

s denotes suitable joint making material, which may be used if desired.

It will be seen from the drawings that the battens may be readily adjusted if required, or removed.

Referring now to the hatch illustrated in Fig. 10 the mode of sealing is similar to that described with reference to the chamber door, with the exception that, in this case, recesses *t* are provided in the beam *u* and combing respectively, into which recesses the battens are adapted to project.

Referring now to Figs. 11 to 13, inclusive:-

Extending longitudinally of the van *v* are upper and lower tracks, each of which is composed of a pair of channel irons *w*, *w* supported by suitable brackets; between each pair of channels are placed wheeled runners *x*.

Revolutely engaging with said runners *x* are cranks *y*, upper and lower cranks being coupled together by rods *z*; said cranks *y* are secured to the front panel *e* of the door by means of brackets *l*; and on said cranks

y are secured arms 2, each arm being pivotally connected to a handle lever 3. When the door is unlocked by moving said jambs or battens to their retracted positions 5 through the actuation of lever 4, lever 3 is pulled by the operator with the result that, as said cranks *y* are free to turn, the door moves bodily outward clear of its frame; said door may then be pushed on its runners 10 in one direction or other away from the opening.

Having now described my invention, what I claim as new, and desire to secure by Letters Patent:—

15 The combination with a doorway and door therefor, of corner pieces fitted in said

doorway, battens carried by the edges of said door, said battens having the ends thereof cut away so as to overlap and beveled so as to engage the corner pieces of 20 said doorway, and means carried by said door adapted for simultaneously moving said battens to engage walls of said doorway and the corner pieces thereof.

Dated this 7th day of January, 1919.

25

In witness whereof I affix my signature in the presence of two witnesses.

ALBERT CHARLES DAVIS.
